United States Patent Office

Des. 181,141
Patented Oct. 8, 1957

181,141

BRASSIERE

Raymond Gould, Yonkers, N. Y., assignor to Helen of Troy, Inc., New York, N. Y., a corporation of New York

Application April 5, 1957, Serial No. 45,607

Term of patent 14 years

(Cl. D20—4)

Fig. 1 is a front elevational view of a brassiere showing my new design; and

The dominant features of my design reside in the portions shown in full lines.

I claim:

The ornamental design for a brassiere, substantially as shown and described.
